F. H. ROYCE.
PISTON FOR RECIPROCATING ENGINES.
APPLICATION FILED DEC. 13, 1920.

1,403,641.

Patented Jan. 17, 1922.

Inventor: Frederick Henry Royce.
Attorney: R. Haddan.

UNITED STATES PATENT OFFICE.

FREDERICK HENRY ROYCE, OF DERBY, ENGLAND, ASSIGNOR TO ROLLS-ROYCE
LIMITED, OF DERBY, ENGLAND.

PISTON FOR RECIPROCATING ENGINES.

1,403,641.

Specification of Letters Patent. Patented Jan. 17, 1922.

Application filed December 13, 1920. Serial No. 430,344.

To all whom it may concern:

Be it known that I, FREDERICK HENRY ROYCE of Nightingale Road, Osmaston, Derby, in the county of Derby, England, a subject of the King of England, have invented certain new and useful Improvements in Pistons for Reciprocating Engines, of which the following is a specification.

This invention relates to pistons of the trunk type, that is to say, those in which the duty of the piston proper is combined with that of a cross-head, the walls of the cylinder acting as the cross-head guide.

In connection with such pistons there is a tendency, owing to the angularity of the connecting rod, for the piston to be thrown (generally on the power stroke) to one side of the cylinder and this causes an audible noise generally known as a "knocking," and whilst many devices have been resorted to in order to obviate this knocking, the present invention comprises a novel or improved means for obviating same, as herein-after fully described and specifically pointed out in the appended claims.

An embodiment of the invention is illustrated in the accompanying drawings, wherein Fig. 1 is a side elevation of an improved piston, Fig. 2 is a vertical central section thereof, and Figs. 3 and 4 are horizontal sections on the lines 3-3 and 4-4 respectively of Fig. 2.

The skirt *a* of the piston *b* is divided vertically into two parts *b*¹ *b*² from the bottom upwards for nearly the whole of its height by means of a split or cutaway part *c*. One of such parts *b*¹ is rigid and contains the pin *d* of the connecting rod *d*¹ and constitutes the main part of the skirt *a*. The other part *b*² is flexible and is subjected to the action of a spring and stop herein-after referred to. The part *b*² constitutes a comparatively small part of said piston skirt and is most remote from the side of the piston which is thrown against the cylinder wall on the power stroke.

Within the skirt are fixed by means of bolts *e*¹ and nuts *e*³ a steel or other suitable spring *e*, preferably of the sugar tongs type, which forces the flexible part *b*² of the skirt outward, and an adjustable stop in the form of heads *e*² on the bolts *e*¹ which limits the extreme outward position of the part *b*².

The spring *e* exerts a force sufficient, but

not more than sufficient, to ensure that the flexible part *b*² of the skirt will not be displaced by the angular force exerted on the piston during the compression stroke.

By means of this arrangement, the stop constituted by the bolts *e*¹ and heads *e*² can be adjusted so that the flexible part *b*² will exert pressure on the wall of the cylinder sufficient to hold the piston constantly in contact with the wall on the other side and at the same time avoid any undue friction on the wall by reason of the action of the spring, and further, if it should happen that the skirt should expand beyond the minimum clearance allowed, owing to its coefficient of expansion under heat being greater than that of the metal of the cylinder, or owing to the faulty adjustment of the stop or for any other reason, the flexible part will yield, whereby no seizure will take place and the abnormal friction will be limited by the effective power of the spring, which is predetermined as above explained.

The invention is also applicable to slipper pistons, such as the Ricardo type.

What I claim as my invention and desire to secure by Letters Patent of the United States is:—

1. A piston for reciprocating engines divided longitudinally by means of a split or cut-away portion into a relatively-large, rigid member and a relatively-small, flexible member, and a spring acting on the flexible member for automatically forcing it outwardly of the piston.

2. A piston for reciprocating engines divided longitudinally into two connected members by means of a split or cut-away portion, one of said members being rigid and the other flexible, a spring acting on the flexible member for forcing it outwards, and means for limiting the outward movement of said flexible member.

3. A piston for reciprocating engines divided longitudinally by means of a split or cut-away portion into a relatively-large, rigid member and a relatively-small, flexible member, a spring acting on the flexible member for automatically forcing it outwardly of the piston, and adjustable means for limiting the outward movement of said flexible member.

4. A piston for reciprocating engines having a skirt portion formed with a flexible

member produced by longitudinally slitting said skirt, a spring secured within the skirt and adapted to exert outward pressure on said flexible member, and adjustable abutment means for limiting the outward thrust of said spring or flexible member.

In witness whereof I have signed this

specification in the presence of two witnesses.

FREDERICK HENRY ROYCE.
